UNITED STATES PATENT OFFICE.

ERNEST FOWLER, OF SEATTLE, WASHINGTON.

RECEPTACLE AND CLOSURE THEREFOR.

1,134,524.

Specification of Letters Patent.

Patented Apr. 6, 1915.

Application filed May 1, 1913. Serial No. 764,887.

To all whom it may concern:

Be it known that I, ERNEST FOWLER, a citizen of the United States of America, and a resident of the city of Seattle, in the county of King and State of Washington, have invented certain new and useful Improvements in Receptacles and Closures Therefor, of which the following is a specification.

10 My invention has for its primary aim to provide a receptacle with a novel closure therefor which will perform its function in an efficient manner and which may be easily manipulated.

15 A further object resides in the mounting of the closure on the receptacle whereby the former may be retained in any position to which it is moved.

With the above and other objects in view, 20 reference is to be had to the following description, the annexed claim, wherein those features of construction, arrangements and combinations of parts on which I desire protection are succinctly defined, and the accompanying drawing, wherein—

Figure 1 is a vertical sectional view of a receptacle embodying my invention and disclosing a tooth brush therein for the purpose of illustration, and Fig. 2 is a horizontal cross section taken on line 2—2 of Fig. 1.

Referring more in detail to the drawing, wherein like characters of reference indicate like parts throughout: 1 designates a receptacle body provided with a partition 8 and 35 having its upper end closed by a wall 1' and provided with an apertured lug 2 extending upwardly from said wall whereby the receptacle may be supported in a convenient manner. The lower end of the receptacle which 40 is open is provided with a closure 3, the same being formed with a recess extending on opposite sides of partition 8 and adapted to receive disinfecting material 4.

Closure 3 is mounted for yielding movement as well as pivotal, such mounting consisting of a pivot pin 5 secured to boss 6 of closure 3 and projecting upwardly from the latter to be guided by the apertured ears or lugs 7 stamped from or otherwise formed on 50 partition wall 8. This wall divides the receptacle into main and auxiliary compartments, the former being for the reception of the tooth brush or other inclosed article while the latter is provided as a housing for pin 5 and the co-operating spring 9. It is of

course obvious that the auxiliary compartment does not have to extend the length of receptacle 1. It does, however, communicate with the recess of closure 3 so as to receive the rising fumes from the disinfectant, and 60 further through the formation of ears 7, apertures are formed in partition walls, permitting of circulation of air between the compartments, particularly when closure 3 is in open position. Spring 9 which receives the upper terminal of pin 5 has its bearings on head 5' of said pin and the uppermost of lugs 7. Closure 3 is provided with an external flange 3' which abuts the lower edge of receptacle 1 to limit the inward movement of the closure, under the influence of spring 9, and also to provide a suitable grip when it is desired to open the closure, said flange projecting beyond the outer surface of the receptacle for such purpose. Spring 9 in addition to holding the closure in its operative position also retains 70 said closure in frictional engagement with the receptacle in the various positions assumed when opening the latter. Pin 5 is 75 provided with a shoulder 5'' intermediate the spaced lugs 7, which is adapted for engagement with the lower of said lugs to limit the compression of the spring 9 when manipulating the closure.

Having thus described my invention, what I claim as new, and desire to secure by Letters Patent of the United States of America, is:

As an article of manufacture, a receptacle 90 body opened at its lower end and having a partition extending substantially the length of the body to provide a pair of compartments, ears struck from the partition thereby providing apertures in the latter establishing communication between the compartments of the receptacle body, a closure for the opened end of the body formed in its inner face with a recess adapted to hold a disinfectant and normally being in communication with both of the compartments of the receptacle body, a pivot pin slidable in the ears and connected to the closure for supporting the latter.

Signed at Seattle, Washington, this 24th 100 day of April 1913.

ERNEST FOWLER.
